DESIGN FOR A TIE RACK

Arthur Waterman, Philadelphia, Pa.

Application August 19, 1946, Serial No. 132,635

Term of patent 14 years

(Cl. D33—8)

To all whom it may concern:

Be it known that I, Arthur Waterman, a citizen of the United States, residing in Philadelphia, Philadelphia County, Pennsylvania, have invented a new, original and ornamental Design for a Tie Rack, of which the following is a specification, reference being had to the accompanying drawings, forming a part thereof.

Fig. 1 is a front elevational view of a tie rack showing my new design;

Fig. 2 is a side elevational view of the tie rack, and

Fig. 3 is a section on line 3—3 of Fig. 1.

I claim:

The ornamental design for a tie rack, as shown.

ARTHUR WATERMAN.
